UNITED STATES PATENT OFFICE.

EUGEN FINAZZER, OF PIEVE-BUCHENSTEIN, AUSTRIA-HUNGARY.

FASTENING DEVICE FOR LADIES' HATS.

1,162,761.

Specification of Letters Patent.

Patented Dec. 7, 1915.

Application filed May 23, 1914. Serial No. 840,591.

To all whom it may concern:

Be it known that I, EUGEN FINAZZER, a subject of the Emperor of Austria-Hungary, residing at Pieve-Buchenstein, in the Empire of Austria-Hungary, have invented certain new and useful Improvements in Fastening Devices for Ladies' Hats, of which the following is a specification.

This invention relates to improvements in 10 fastening devices for ladies' hats described and shown in my prior application Serial Number 794,402.

According to this invention the hooks are arranged in pairs, one hook of each pair being fixed in the sleeve, the other hook of the same pair being fixed to a spring influenced rod movably mounted in said sleeve so that the hooks approach each other and clamp in 20 the hair if the rod is pushed inward.

With this and other objects in view the invention consists in the particular construction and arrangement of parts as hereinafter described and shown in the accompanying drawings by way of example.

Figure 1 is a longitudinal section of the improved fastening device for ladies' hats. Fig. 2 is a section on line I—I of Fig. 1. Fig. 3 is a side elevation of the fastening device.

30 Hooks *e* are fixed on the sleeve *b* which is acted upon by the spring *a*. The sleeve is movably mounted on a rod fixed by means of a disk *c* inside the hat. In the sleeve *b* a rod *f* is arranged and between the inner end 35 of this rod *f* and a disk *h* a spiral spring *g* is located. A ringshaped projection *i* in sleeve *b* serves as abutment for the disk *h* and for the inner enlarged end of the shaft of disk *c*. The rod *f* carries hooks *e* projecting through longitudinal slots *k* of the sleeve. Into the open end of the sleeve *b* a pin *n* is pushed which is provided with a 40 large head. This pin *n* has a longitudinal cavity in which a blade spring *p* with a projection *o* is located. This projection *o* of the blade spring is designed to engage with 45 one of the openings *g*, *g'* of the sleeve *b*.

The fastening device operates as follows: If the pin *n* is pushed into the sleeve *b* the 50 projection *o* of the blade spring *p* engages with the opening *g* of the sleeve *b* and said sleeve can now be turned by means of the large head of said pin so that end hooks *e*

and *l* penetrate into the hair. If now the blade spring *d* is depressed and the pin 55 pushed farther into the sleeve *b* the rod *f* is pushed to the left against the action of the spiral spring *g* whereby the hooks *e* are moved toward the hooks *l* and the hair is clamped in between said two hooks. The 60 different parts are secured in their position by the projection *o* engaging with the second opening *g'* of the sleeve *b*.

The device can further be used in another manner as follows: The thin end is directly 65 pushed into the sleeve *b* so that the projection *o* of the blade spring *p* engages with the opening *g'* so that the hooks *e* and *l* are pushed against one another and penetrate together into the hair when the sleeve *b* is 70 being turned. If the pin *n* is pulled out of the sleeve so that the projection *o* engages with the opening *g* the rod *f* is pushed back through the action of the spring *g* so that the hooks *l* move away from the hooks *e*. 75 If in this position of the device the sleeve *b* is further turned and pushed to the left against the action of the spring *a* the hooks grip again other strains of hair whereby the hat is securely fixed on the head. 80

I claim:

An improved fastening device for ladies' hats comprising in combination a sleeve adapted to be arranged inside the hair, said sleeve having a longitudinal slot and a notch 85 at the outer end, a hook fixed on the sleeve at the inner end of said slot, a rod movably mounted in said sleeve, a hook fixed to said rod and projecting through said slot, a projection in said sleeve, a spiral spring 90 enclosed between said projection and the inner end of said movable rod, a pin adapted to be movably mounted in the hat wall opposite the end of said sleeve and having a longitudinal cavity, a blade spring mounted in said 95 cavity of the pin, and a projection on the blade spring, said projection adapted to engage with the notch of the sleeve when said pin is pushed in, substantially as described and shown and for the purpose set forth. 100

In witness whereof I have hereunto set my hand in the presence of two witnesses.

FINAZZER EUGEN.
